(57) **CLAIM**

The ornamental design for a support for an electronic camera, as shown and described.

DESCRIPTION

FIG. 1 is a front perspective view of a support for an electronic camera showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a front perspective view of the support for an electronic camera of FIGS. 1-7 shown with an illustrative, disclaimed electronic camera in broken lines;

FIG. 9 is a front view thereof;

FIG. 10 is a rear view thereof;

FIG. 11 is a right side view thereof;

FIG. 12 is a left side view thereof;

FIG. 13 is a top view thereof;

FIG. 14 is a bottom view thereof;

FIG. 15 is a front perspective view of the support for an electronic camera of FIGS. 1-7 shown in a different illustrative style

FIG. 16 is a front view thereof;

FIG. 17 is a rear view thereof;

FIG. 18 is a right side view thereof;

FIG. 19 is a left side view thereof;

FIG. 20 is a top view thereof; and,

FIG. 21 is a bottom view thereof.

The broken line showing of elements of the support for an electronic camera in FIGS. 1-14 and the electronic camera in FIGS. 8-14 is for environmental purposes only and forms no part of the claimed design.
